MODULATED-CARRIER WAVE-SIGNAL-TRANSLATING SYSTEM

Madison Cawein, Manhasset, N. Y., assignor to
Hazeltine Corporation, a corporation of Delaware

Application November 12, 1938, Serial No. 239,981

4 Claims. (Cl. 178—7.5)

This invention relates to modulated-carrier wave-signal-translating systems and particularly to such systems whereby a carrier wave modulated in a desired polarity may be derived from another carrier wave modulated in opposite polarity. The invention is especially useful in television receivers embodying cathode-ray reproducing tubes arranged for grid detection.

In certain carrier-wave signal-translating systems, it is necessary or desirable to use a carrier wave which is modulated by the signal components in a particular polarity. Frequently, however, the only available signal comprises a carrier wave modulated by the signal components in a polarity opposite to that desired. In this case, if the available signal is to be utilized, some means must be provided whereby a carrier wave modulated in the desired polarity may be derived therefrom. Entirely satisfactory systems for accomplishing this purpose have heretofore not been available.

For example, in television receivers of the cathode-ray tube type, the reproducing tubes themselves are sometimes arranged to effect the required detection of the signal from the carrier wave avoiding the requirement of a separate detector. For such receivers, it is essential that the carrier wave applied to the reproducing tube be of the positively-modulated type; that is, that the signal components be so impressed upon the carrier wave that increases in carrier amplitude correspond to increases in light intensity. However, certain television broadcast systems now proposed develop and transmit negatively-modulated carrier waves in which the signal components are so impressed upon the carrier wave that decreases in its amplitude correspond to increases in light intensity.

Heretofore, in order to derive a carrier wave modulated in one polarity from a carrier wave modulated in an opposite polarity, it has been necessary, first, to detect the available carrier wave, thereby to derive its modulation components, and then to modulate an independently developed unmodulated-carrier wave in the desired polarity with the detected signal components. For various reasons, including its requirement of relatively complicated apparatus, this method has not proved entirely satisfactory.

It is an object, therefore, of the present invention to provide an improved system whereby a carrier wave modulated by signal components in a desired polarity may be derived from another carrier wave modulated by the signal components in an opposite polarity.

A further object of the invention is to provide an improved television receiver of the cathode-ray tube grid-detection type which is adapted to receive and reproduce either a positively- or negatively-modulated carrier wave.

In accordance with the present invention, there is provided a signal-translating system which comprises means for translating a first carrier wave of a predetermined frequency and modulated in one polarity by signal components. Means are further provided for generating a second unmodulated-carrier wave of said predetermined frequency but substantially 180 degrees out of phase with respect to the first wave. The system includes means responsive to variations in the amplitude of the first carrier wave and independent of its signal modulation for controlling the generating means to maintain the ratio of the peak amplitudes of the first and second waves substantially constant. Means are further provided for combining the first and second waves to derive a third carrier wave of the aforementioned predetermined frequency modulated by the signal components in a polarity opposite to that of the modulation of the first wave.

Further in accordance with the present invention, a television signal-reproducing system is provided which is adapted for the reception of a television carrier wave negatively-modulated by modulation signal components. This system comprises a cathode-ray signal-reproducing tube of the self-detection type. Means are arranged to derive from a received negatively-modulated carrier wave a carrier wave of the same frequency but modulated positively by the signal components of the received wave. The positively-modulated wave is applied by suitable means to the input circuit of the self-detecting reproducing tube.

For a better understanding of the invention, together with other and further objects thereof, reference is had to the following description taken in connection with the accompanying drawing and its scope will be pointed out in the appended claims.

In the accompanying drawing, Fig. 1 is a circuit diagram, partially schematic, of a complete television signal-receiving system including an arrangement for deriving a positively-modulated carrier wave from a received negatively-modulated carrier wave in accordance with the present invention, while Fig. 2 is a group of wave forms illustrating the operation of the invention.

Referring now more particularly to Fig. 1, the system illustrated comprises a television receiver

of the superheterodyne type including an antenna system 10, 11, connected to a radio-frequency amplifier 12 to which are connected in cascade, in the order named, an oscillator-modulator 13, 5 an intermediate amplifier 14, a further intermediate amplifier 15, which comprises a part of the system of the present invention as is herein-after described in more detail, and a cathode-ray signal-reproducing tube 16. 10 The cathode-ray tube 16 comprises the usual envelope 17 containing, in the order named, a cathode 19 having a heater 20, a signal input electrode or control grid 21, a screen 22, a first anode 23, a second anode 24, and the usual fluorescent 15 screen 25 at the end of the tube. Line-frequency and field-frequency scanning coils 16a and 16b are disposed about the neck of the tube for deflecting the beam in two directions normal to each other. The output circuit of the amplifier 20 tube 15a is connected to the control grid 21 by way of a series condenser 26 and leak resistor 27, providing a time-constant input circuit whereby grid detection of a modulated carrier applied thereto is effected in the well-known manner. 25 Operating potentials are supplied to the electrodes of the cathode-ray tube from a suitable source, such as battery 28. A line-frequency generator 29 and a field-frequency generator 30 are coupled to an output circuit of the intermediate-frequency amplifier 14 by way of a synchronizing signal separator 31, which serves in a conventional manner to separate the synchronizing pulses from the carrier wave, from the other modulation components, and from each other, in 30 the usual manner.

The stages of units just described may all be of conventional well-known construction so that detailed illustrations and descriptions thereof are unnecessary herein. Referring briefly to the 40 operation of the system described above as a whole, television signals intercepted by the antenna circuit 10, 11 are selected and amplified in the radio-frequency amplifier 12 and supplied to the oscillator-modulator 13, wherein they are 45 converted into intermediate-frequency signals, which, in turn, are first selectively amplified in the intermediate-frequency amplifiers 14 and 15 and then impressed upon input circuit 26, 27 of the cathode-ray signal-reproducing tube 16. 50 With proper operating potentials supplied from the battery 28 to the electrodes of the tube 16, the electron beam is emitted from the cathode and accelerated and focused into a beam by the electrodes 21-24 to strike the target 25. The 55 input circuit 26, 27 cooperates with the control grid 21 to effect grid detection of the carrier wave so that the cathode ray developed by the tube is modulated; that is, its intensity is controlled in accordance with the video-frequency signal components. If desired, the cathode-ray tube may be arranged for target detection, in which case the time-constant input circuit is omitted and the control grid is simply connected by a coupling condenser to the amplifier 15, the target of the 60 cathode-ray tube itself effecting the signal detection in the well-known manner.

The intermediate-frequency carrier wave is also supplied to the separator 31, wherein the line-synchronizing and field-synchronizing signal components are derived, separated from each other, and applied to the generators 29 and 30, respectively, to synchronize the operation thereof. Saw-tooth current waves generated in the line-frequency and field-frequency generators 29 70 and 30 are applied to the scanning elements 16a

and 16b to produce electric scanning fields, thereby to deflect the ray in two directions normal to each other so as to trace a rectilinear scanning pattern on the screen of the target to reconstruct the transmitted picture.

Referring now more particularly to the portion of the system of Fig. 1 embodying the present invention, for the purpose of deriving a positively-modulated-carrier wave from a received negatively-modulated-carrier wave, there is provided in connection with the amplifiers 14 and 15 an intermediate-frequency carrier-wave generator 32 and an amplifier 33. The generator 32 may be of any suitable construction and comprise a conventional oscillator designed to develop a second intermediate-frequency carrier wave of the same frequency as that of the first intermediate-frequency carrier wave developed by the oscillator-modulator 13. The generator 32 is so controlled that this second carrier wave, 10 while being of the same frequency as the first carrier wave, is 180 degrees out of phase with respect thereto. A synchronizing connection 32a is provided between suitable points in the amplifier 14 and the generator 32 to maintain the operation of the generator 32 at the desired frequency and phase with respect to the first intermediate-frequency carrier wave. The repeater or amplifier tubes 15a and 33 may be of identical design, preferably of the pentode type, 20 and together comprise a combining amplifier. The input circuits of tubes 15a and 33 are connected to the amplifier 14 and generator 32 by way of transformers 34 and 35, respectively, each tuned to the intermediate frequency. A common 25 load circuit or parallel output circuit is provided for these tubes comprising a resistor 36 and an inductance 37, by way of which operating voltage is supplied to the anodes of the tubes from a suitable source indicated at +B. The suppressor 40 grids of the tubes are connected directly to their cathodes and screen potential is supplied from a suitable source indicated at +Sc.

For the purpose of maintaining substantially constant the ratio of the peak amplitudes of the 45 modulated- and unmodulated-carrier waves as applied to the input circuits of the tubes 15a and 33, there is provided a rectifier 38 energized by means of a winding 39 forming a part of the transformer 34. A load circuit comprising a 50 parallel-connected resistor 40 and condenser 41 and having a suitable time constant is provided for the rectifier, as shown. The positive end of the load resistor 40 is connected by way of a filter, including a series resistor 42 and a shunt 55 condenser 43, and by way of the secondary winding of the transformer 35, to the control grid of the tube 33. The rectifier 38 operates in conventional manner to peak-rectify the intermediate-frequency carrier wave derived from the received 60 signal, thereby to develop a unidirectional-bias voltage proportional to the peak value and, hence, the average intensity of this carrier wave independent of light modulation components. This bias voltage is applied positively to the control 65 grid of the tube 33 thereby to control the amplitude of the unmodulated-carrier-wave output of this tube directly in accordance with variations in the average amplitude of the first or received carrier wave so as to maintain the ratio of the 70 peak amplitudes of the two waves substantially constant.

Switches S₁ and S₂ are preferably included in the lead 32a to the generator 32 and in the connection between the anode of the tube 33 75

and the load circuit 36, 37, respectively, and are adapted for operation by a unicontrol member U so that this part of the system may be disconnected when its use is not desired, as when a positively-modulated-carrier wave is being received.

The general operation of the system of the invention may best be described in connection with the wave forms of Fig. 2. Curve A represents schematically a portion of a negatively-modulated television-carrier wave such as may be received by the receiver of Fig. 1. The portions of the wave indicated at S represent synchronizing pulses while between these pulses are the video-frequency modulated portions of the signal, decreasing carrier amplitude corresponding to increasing light intensity. The signal levels corresponding to black and white are indicated at B and W, respectively. The unmodulated-carrier wave developed by the generator 32 is, of course, of substantially uniform amplitude and is not shown. The first carrier wave, modulated as just described, is applied to the input circuit of the tube 15. The unmodulated-carrier wave developed by the generator 32 with the same frequency as, but 180 degrees out of phase with respect to, the first carrier wave is applied to the input circuit of the tube 33, the ratio of the peak amplitudes of two carrier waves being maintained substantially constant, as described above. The two carrier waves are combined, or algebraically added, in the common output circuit 36, 37 of the tubes 15, 33, and a third carrier wave is thereby developed which is of the same frequency as the first carrier wave and is modulated with the same signal components, the modulation in this case, however, being of positive polarity, that is, of a polarity opposite to that of the modulation of the first carrier wave.

When the system is adjusted so that the unmodulated-carrier wave has the same amplitude as the peak amplitude of the main modulated-carrier wave, there is developed a 100 per cent positively-modulated-carrier wave having a wave form such as illustrated by curve B. That is, in this wave, increases in carrier amplitude represent increases in light intensity so that it is suitable for direct application to the input circuit of the cathode-ray tube 16, to which it is applied by way of the condenser 26, as shown. Being 100 per cent modulated, the amplitude of the carrier wave is reduced to zero for peak values of the modulation voltages in the black direction.

In case a wave less than 100 per cent modulated is desired, it may be developed by simply adjusting the generator 32 so that the unmodulated carrier has an amplitude greater than the peak amplitude of the main carrier wave. A wave similar to that represented by curve B but having less than 100 per cent modulation is indicated by curve C of Fig. 2. The signal components and shade levels are indicated on the curves B and C by the same reference letters as used in connection with the curve A.

While the present invention has been described in connection with a particular type of television receiver, it will be appreciated that it is of general application and may be utilized in any signal-translating system, whether receiver or transmitter, for the purpose of deriving a carrier wave having modulation in one polarity from another carrier wave having modulation of an opposite polarity.

While there has been described what is at pres-

ent considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A signal-translating system comprising, 10 means for translating a first carrier wave of a predetermined frequency and modulated in one polarity by signal components, means for generating a second unmodulated-carrier wave of said predetermined frequency but substantially 15 180 degrees out of phase with respect to said first wave, means responsive to variations in the amplitude of said first carrier wave and independent of its signal modulation for controlling said generating means to maintain the ratio of the peak 20 amplitudes of said first and second waves substantially constant, and means for combining said first and second waves to derive a third carrier wave of said predetermined frequency modulated by said signal components in a polarity 25 opposite to that of the modulation of said first wave.

2. A signal-translating system comprising a vacuum-tube repeater having an input circuit, means for applying to said input circuit a first 30 carrier wave of a predetermined frequency modulated by said frequency components in one polarity, a second vacuum-tube repeater having an input circuit, means for generating a second unmodulated-carrier wave of said predetermined 35 frequency but 180 degrees out of phase with respect to said first wave and having a peak amplitude at least as great as that of said first wave, means for applying said second wave to said input circuit of said second repeater, means for controlling said generating means to maintain the ratio of the peak amplitudes of said first and second waves substantially constant, and a common output circuit for said two repeaters for deriving a third carrier wave of said predetermined 40 frequency modulated by said signal components in a polarity opposite to that of the modulation of said first wave.

3. A signal-translating system comprising a vacuum-tube repeater having an input circuit, 50 means for applying to said input circuit a first carrier wave of a predetermined frequency modulated by said signal components in one polarity, a second vacuum-tube repeater having an input circuit, means for generating a second unmodulated-carrier wave of said predetermined 55 frequency but 180 degrees out of phase with respect to said first wave and having a peak amplitude at least as great as that of said first wave, means for applying said second wave to said input 60 circuit of said second repeater, means for developing a control-bias voltage proportional to variations in the amplitude of said first carrier wave and independent of its signal modulation, means for applying said control voltage as a bias to said 65 generating means to maintain the ratio of the peak amplitudes of said first and second waves substantially constant, and a common parallel output circuit for said two repeaters for deriving a third carrier wave of said predetermined 70 frequency modulated by said signal components in a polarity opposite to that of the modulation of said first wave.

4. A television signal-reproducing system adapted for the selective reception of television- 75

carrier waves of any of a plurality of predetermined frequencies and modulated either negatively or positively by signal components, comprising a cathode-ray reproducing tube of the self-detecting type and including a control electrode, means for applying received carrier waves of the positively-modulated type directly to said control electrode, separate means for developing from received carrier waves of the negatively-

modulated type a second television carrier wave of the same predetermined frequency positively modulated by the signal components and for applying said developed carrier wave to said control electrode, and means for selectively connecting said separate means in circuit in said system only for the reception of negatively-modulated carrier waves. 5
